ARCHIBALD K. CROSSMAN, OF OAKLAND, CALIFORNIA

NONGLARE REFLECTOR

Application filed February 29, 1932. Serial No. 595,759.

This invention is a non-glare reflector particularly adapted to the headlights of automotive vehicles, and is intended to suitably break up or deflect the direct rays from the 5 headlight which cause the blinding glare so prevalent in the usual headlight, without the interposition of special lenses which are now used to minimize the glare.

The main object of this invention therefore, is to provide a non-glare reflector, one 10 which will properly break up the rays which cause the glare common with ordinary reflectors.

Another object of the invention is to provide a non-glare reflector which is easily and 15 cheaply constructed and requires no additional parts for the purpose of obviating the usual glare of the headlight.

Other objects and advantages of the invention 20 will become apparent as the following description is read on the drawing forming a part of this specification and in which similar reference characters are used to indicate similar parts throughout the several views 25 of which

Fig. 1 is a front elevation of the invention; 30 Fig. 2 is a sectional elevation through the focal center of the non-glare means;

Fig. 3 is a section taken on line 3—3 of Fig. 2.

Fig. 4 is a diagrammatic view indicating 35 the function of the non-glare means.

The invention consists of the usual parabolic reflector 10, which is provided with the 40 usual flange 11 for mounting, and a lamp socket 12, all of which are of standard construction and therefore require no description of form or function. The parts as described so far do not form a part of the invention, which consists in forming diametrically opposed insets 13 and 14 which are 45 formed substantially as shown in Fig. 3, being of substantially V form and suitably rounded at the vertex as indicated at 15 and at the base as indicated at 16, a plan view showing the base to be substantially elliptical in form, and the ridge 15 forms a substantially straight line from the periphery 50 of the reflector to the lamp socket, as shown in Fig. 2. This operation of insetting may

be performed before or after forming of the standard reflector, and may be performed on existing reflectors which is a feature having considerable merit.

Fig. 4 indicates the function of these insets. The rays which cause the usual glare are reflected from the upper and lower portions of the reflector, which portions are included in the insets shown in Fig. 1. Rays 55 of light from lamp 17 striking on the exact center 18 of the inset are directed straight ahead while any rays 19 or 20 strike the sides of the inset and are either dispersed or directed to the normal part of the reflector 60 where they are again changed in direction. Therefore substantially all of the rays adapted to cause glare are broken up and dispersed, the reflector retaining substantially full efficiency without the attendant glare.

The reflector may be substituted for any 65 standard reflector of the same size so that no changes are required in the housing or other elements of standard lamps.

Having described an operative device it 70 will be noted that variations in construction and arrangement, or form which are consistent with the appended claims may be resorted to without detracting from the spirit or scope of the invention or sacrificing any of 75 the advantages thereof.

I claim:

1. A reflector comprising a main reflector element of substantially parabolic form and having a lamp mounting socket positioned at the focal axis thereof, a light deflector element above said socket and a second light deflecting element below said socket, each of said light deflecting elements consisting of a single straight ridge connecting the periphery of the socket and the periphery of the reflector and being disposed in a vertical plane 85 relative to the focal axis, said deflecting elements having plane inclined sides and each intersecting the parabolic surface in a curve 90 having an ovate form.

2. A reflector comprising a main reflector element of substantially parabolic form and having a lamp mounting socket positioned at the focal axis thereof, a light deflector element above said socket and a second light de- 100

flector element below said socket, each of said light deflecting elements consisting of a single straight ridge connecting the periphery of the socket and the periphery of the reflector and being disposed in a plane perpendicular to the focal axis, said deflecting elements each being V-shaped in transverse cross-section and intersecting the parabolic surface in a curve having an ovate form.

10 In testimony whereof I affix my signature.
ARCHIBALD K. CROSSMAN.
